OIL CIRCUIT BREAKER

Benjamin P. Baker, Turtle Creek, and Robert C. Dickinson, Wilkinsburg, Pa., assignors to Westinghouse Electric Corporation, East Pittsburgh, Pa., a corporation of Pennsylvania

Application January 29, 1944, Serial No. 520,254

15 Claims. (Cl. 200—150)

1

This invention relates to circuit breakers of the liquid immersed type and particularly to contact and arc-extinguishing structures therefor.

It is an object of the invention to provide a simple and inexpensive arc-extinguishing structure which is effective for interrupting both high and low currents.

Another object of the invention is to utilize the moving contact as a piston for providing a flow of arc-extinguishing liquid to extinguish the arc.

A further object of the invention is to utilize a single arc-extinguishing structure into which a bridging contact member is movable to draw two arcs, one at each end of the bridging member.

It is also an object of the invention to mount the arc-extinguishing structure at a distance from a stationary contact so that the extinguishing structure does not cover the contact and prevent inspection of the contacts.

Another object in having the arc-extinguishing structure spaced from the stationary contact is to give the further advantage that an isolating gap of insulating liquid is provided between the stationary contact and the extinguishing structure, so that good insulation is obtained between the stationary and moving contacts immediately after arc extinction and before the moving contact has moved to full open position. This reduces the tendency toward reignition of the arc over the surface of the extinguishing chamber if it should become coated with carbon.

An additional object of the invention lies in the provision of a structure in which the moving contact is allowed to move freely to quickly obtain sufficient arc length for interruption during the initial part of the opening stroke, and is then lengthened more slowly within an interrupting structure which begins to extinguish the arc after the initial part of the opening operation. This keeps the arc energy to a minimum and requires only a minimum of mechanical power to open the circuit and extinguish the arc.

A further object of the invention is to utilize the kinetic energy, which is stored in the moving contact during its initial movement, to move the arc extinguishing liquid to assist in interruption of the arc. This useful dissipation of the kinetic energy of the moving contact eliminates any necessity for providing dashpots for stopping the contact and preventing bouncing thereof.

It is another object of the invention to so arrange the contacts and arc-extinguishing structure that the magnetic force of the current loop

2

assists in driving the moving contact in opening direction, and to utilize this magnetic driving force to give piston action for moving liquid through the arc to extinguish it. This is particularly effective for the interruption of heavy currents where the magnetic forces are large.

Another object of the invention is to initially draw the arc outside of the arc-extinguishing chamber so as to permit immediate escape of the arc gases until the arc has been lengthened sufficiently to permit interruption. This ease of escape for the gas first formed keeps the pressure in the arc-extinguishing chamber low until the pressure can be used effectively to extinguish the arc without reignition. The arrangement prevents destructive pressures from building up with the initial rise of arc voltage, as has taken place in prior art structures before the vents have been denuded of the arc-extinguishing liquid which blocks the escape of gas.

Other objects and advantages of the invention will be apparent from the following description of the specific modifications shown on the drawing, in which:

25 Figure 1 is an elevational view of a circuit breaker embodying the invention, with the tank broken away to show the contact and arc-extinguishing structure. The contacts are shown in closed position.

30 Figure 2 is an enlarged view in section through the arc-extinguishing chamber showing the contacts in separated position.

Figure 3 is a sectional view through the arc-extinguishing structure taken on the line III—III of Fig. 2 and looking upwardly.

35 Figure 4 is a sectional view similar to Fig. 3 but showing a modified arc-extinguishing structure.

The circuit breaker of the invention is shown 40 for purposes of illustration as comprising a tank 5 containing a body of insulating and arc-extinguishing liquid, such as oil 7. A pair of insulating bushings 9 extend through the top of the tank 5 and have conductors 11 extending therethrough. Stationary contacts 13 are mounted on the lower end of each of the lead-in conductors 11. A unitary arc-extinguishing structure 15 is mounted below the contacts 13 by being suspended from the top 6 of the tank 5 by a pair of insulating rods 17.

45 The interrupting or arc-extinguishing chamber 15 is shown as being built up of a stack of insulating plates 19 and 21. Each of the plates 19 and 21 are oval in shape. The plates 19 have a 50 smaller oval opening 23 than the openings 25 of

the alternate plates 21, so that the arc-extinguishing chamber has a corrugated surface which not only provides a longer breakdown path, but also provides recesses which retain the arc-extinguishing liquid and cause turbulence as the liquid and arc gases flow out of the structure. A bottom plate 27 closes the lower end of the interrupting structure while the upper end is open. It is understood that the lower end of the arc-extinguishing structure need not be completely closed but may have a small bleed or vent opening.

The electrical circuit is completed between the stationary contacts 13 by a conducting bridging member 29 which is mounted on an insulating contact-operating rod 31 which may be actuated by any suitable mechanism for opening and closing the circuit. Moving contacts 33 are mounted on each end of the conducting bridging member 29 for engagement with the stationary contacts 13.

As shown best in Figure 3, the bridging member 29 is made to fit rather snugly within the opening of the arc-extinguishing chamber so as to act as a piston. Passages 35 adjacent the ends of the bridging member 29 and/or openings 37 through the bridging member are provided so that as the bridging member moves into the arc-extinguishing chamber, the liquid under the bridging member is forced by piston action to flow upwardly through the passages 35 and/or 37 and longitudinally through the arc space between the contacts 13 and 33. Insulating barrier members 39 may be mounted on the bridging member 29 for confining the arc and the flow of liquid and gas to the arc space between the contacts 13 and 33.

The upper end of the arc-extinguishing chamber 15 is mounted at a distance from the stationary contacts 13 so that there is a clear gap in the insulating liquid between the contacts 13 and the top of the arc-extinguishing chamber. This provides good insulation immediately after the arc is formed so that if the interior of the chamber should become coated with carbon from decomposed oil, there will be a gap through clean oil to provide insulation, and to render unlikely restriking of the arc over the surface of the chamber after the arc has been once extinguished, even though the moving contact has not yet moved to full open position.

Effective arc-extinguishing action during the interruption of both high and low currents is obtained because of the piston action of the bridging member 29, which causes upward flow of the arc-extinguishing liquid through the arc space between the contacts 13 and 33. If the current being interrupted is small, it will be extinguished largely because of the forced flow of liquid by the bridging and piston member 29 whereas, if the current interrupted is larger, there will be an increased amount of liquid turned into gas which will also flow upwardly and longitudinally of the arc in the space between the contacts 13 and 33. The corrugated internal surface of the arc-extinguishing chamber retains the arc-extinguishing liquid along the arc path and also causes turbulence in the outward flow of gas and liquid to further break up the arc stream.

It will be noted that the current flows in a looped path extending downwardly from one lead-in conductor 11 through one arc to one end of the bridging member 29, then across the bridging member and up through the other arc to the other lead-in conductor 11. During the interruption of heavy currents, this loop tends to en-

large itself because of the magnetic action. This has two advantages. First, the magnetic force acts to move the bridging and piston member 29 downwardly so as to give a stronger piston action. Second, the arcs are moved outwardly into contact with the corrugated end portions of the extinguishing chamber and are held adjacent the pockets which supply oil for extinguishing the arcs.

The fact that the top of the extinguishing chamber 15 is mounted below the stationary contacts 13 has the advantage that the condition of the contacts 13 and their engagement with the moving contacts 33 on the bridging bar 29 when the breaker is closed, may be readily inspected without demounting the arc-extinguishing chamber 15. The space between the stationary contacts 13 and the top of the arc-extinguishing chamber 15 also permits the bridging and piston member 29 to be accelerated during the opening part of its stroke without substantial retarding action. This permits kinetic energy to be stored in the moving contact which is later available for forcing oil to flow by piston action through the arcs. The arc-extinguishing chamber has its greatest retarding effect at the very end of the stroke of the moving contacts, where it is desirable to give dashpot action and bring the moving contacts to rest without bouncing or excessive forces on the operating mechanism.

The spacing of the top of the arc-extinguishing chamber 15 from the stationary contacts 13 also has the advantage that free venting of the arc space is obtained when the arc is first drawn and is of short length. This keeps the pressure low until after the arc has been drawn into the arc chamber, and gives a better flow of gas and liquid after the arc has been drawn to such a length that it may be extinguished. It also prevents the building up of pressures in the arc-extinguishing chamber, which might be destructive unless the chamber is made of extremely strong construction.

The modification shown in Figure 4 is mounted and arranged in the same manner as shown in Figs. 1 to 3, the only difference being in the construction of the end portions of the arc-extinguishing chamber. The plates 41 having the smaller opening 43 are provided with recesses 45 along a slot at each end thereof. Surrounding the slot is a U-shaped recess in which is embedded a U-shaped magnetic member 47. The plates 49 having the larger openings 51 are provided at their ends with narrow slots 53.

When the arc is drawn between the stationary contacts 13 and the moving contacts 33 on the ends of the bridging and piston member 29, a magnetic field is induced in the magnetic members 47 which acts to magnetically draw the arcs into the narrow slots 53 and into the pockets 45. The narrowness of the passage into which the arc is moved provides a strong deionizing action and holds the arc directly in the path of the out-flowing gas and liquid to quickly extinguish it.

It is apparent that the narrow slots 53 and the pockets 45 in the ends of the extinguishing chamber may be used without the use of the magnetic plates 47 since the magnetic repulsion between the two sides of the looped current path may be relied upon for moving the arcs into the narrow slots. In other respects, the modified structure shown in Figure 4 operates in the same manner and with the same advantages set forth in describing the modification shown in Figures 1 to 3.

75 While two specific embodiments of the inven-

tion have been described, it is obvious that other changes and modifications may be made without departing from the spirit and scope of the invention as set forth in the claims.

We claim as our invention:

1. In a circuit breaker, a container of arc-extinguishing liquid, a pair of insulated lead-in conductors extending into the container, a contact on the inner end of each of said conductors, an arc-extinguishing chamber mounted in said container independently of and spaced from the inner end portions of said lead-in conductors and separated by liquid therefrom, bridging means which in closed position completes the electrical circuit between said contacts, said arc-extinguishing chamber having its interior of a size to closely receive said bridging means therein, means for moving the bridging means into the chamber for drawing the arcs into the chamber and forcing liquid to flow out of the chamber through the arc.

2. In a circuit breaker, a container of arc-extinguishing liquid, a pair of insulated lead-in conductors extending into the container, a contact on the inner end of each of said conductors, a stationary arc-extinguishing chamber mounted in said container independently of the inner end portions of said lead-in conductors and separated by liquid therefrom, movable bridging and piston means including conducting material for completing the electrical circuit between said contacts, means for moving said bridging and piston means to open the circuit by moving into said chamber, said bridging and piston means having an area fitting rather snugly into said chamber except adjacent the arcs for forcing liquid to flow through the arcs as it flows out of the chamber when the piston moves in.

3. In a circuit breaker, a container of arc-extinguishing liquid, a pair of insulated lead-in conductors extending into the container, a contact on the inner end of each of said conductors, a single arc-extinguishing chamber for the arcs from both contacts mounted in said container independently of the inner end portions of said lead-in conductors and separated by liquid therefrom, bridging and piston means movable from a position where its end portions engage and complete the electrical circuit between said contacts to a position within said single arc-extinguishing chamber, said bridging and piston means having a portion substantially filling the opening in the arc-extinguishing chamber except for one or more passages adjacent the ends thereof through which liquid is forced to flow by piston action to extinguish both arcs.

4. In a circuit breaker, a container of arc-extinguishing liquid, a pair of insulated lead-in conductors extending into the container, a contact on the inner end of each of said conductors, an arc-extinguishing chamber mounted in said container independently of the inner end portions of said lead-in conductors and separated by liquid therefrom, bridging and piston means movable from a position where its end portions engage and complete the electrical circuit between said contacts to a position within said arc-extinguishing chamber, said bridging and piston means having a portion substantially filling the opening in the arc-extinguishing chamber except for one or more passages adjacent the ends thereof through which said liquid is forced to flow, and said passages being pointed in a direction generally longitudinally of the arc to cause a longitudinal flow through the arc as it is drawn.

5. In a circuit breaker, a container of arc-extinguishing liquid, a pair of insulated lead-in conductors extending into the container, a contact on the inner end of each of said conductors, means of insulating material forming a single arc-extinguishing chamber for the arcs drawn from both of said contacts, bridging and piston means movable from a position where its end portions engage and complete the electrical circuit between said contacts to a position within said arc-extinguishing chamber, said bridging and piston means having a portion substantially the same size as the opening in the arc-extinguishing chamber except for one or more passages through which liquid is forced to flow into contact with the arc adjacent its end on the bridging member and then longitudinally of the arc.

6. In a circuit breaker, a container of arc-extinguishing liquid, a relatively stationary contact mounted in the container and in the arc-extinguishing liquid, stationary means of insulating material forming an arc-extinguishing chamber immersed in said liquid and spaced from said relatively stationary contact only by a gap of said liquid, said arc-extinguishing chamber being substantially closed at its end remote from said relatively stationary contact member and open at its other end, and a contact and plunger member movable away from said relatively stationary contact to draw an arc into the chamber and having a relatively close fit with the interior of said arc-extinguishing chamber at least adjacent its substantially closed end to cause said liquid to flow toward the open end of the chamber through the arc space.

7. In a circuit breaker, a container of arc-extinguishing liquid, a relatively stationary contact mounted in the container and in the arc-extinguishing liquid, means of insulating material forming a stationary arc-extinguishing chamber, said relatively stationary contact and said chamber being mounted at a distance from each other with only a clear gap in said liquid therebetween, said arc-extinguishing chamber being substantially closed at its end remote from said relatively stationary contact member and open at its other end, and a contact and plunger member movable away from said relatively stationary contact to draw an arc into the chamber and having a relatively close fit with the interior of said arc-extinguishing chamber to cause said liquid to flow toward the open end of the chamber through the arc space.

8. In a circuit breaker, a container of arc-extinguishing liquid, a pair of relatively stationary contacts mounted in the container and in the arc-extinguishing liquid, a conducting member for bridging said relatively stationary contacts, a unitary arc-extinguishing device having an open end large enough to receive said conducting bridging member and into which the arcs drawn between the ends of said bridging member and said pair of contacts are both drawn, and said unitary arc-extinguishing device being mounted spaced from said pair of contacts so as to permit visual inspection of the point of engagement of said bridging member with said pair of contacts without disturbing said arc-extinguishing device.

9. In a circuit breaker, a container of arc-extinguishing liquid, a pair of relatively stationary contacts mounted in the container and in the arc-extinguishing liquid, a conducting member for bridging said relatively stationary contacts, arc-extinguishing means including a chamber large enough for movement of said bridging member

therein and having an open end permitting rapid acceleration of the bridging member during the first part of its movement away from the relatively stationary contacts, and said chamber being substantially closed at its other end and having a relatively close fit with said bridging member adjacent said other end for retarding movement of the bridging member and utilizing its kinetic energy to move arc-extinguishing liquid through the arc.

10. In a circuit breaker, a container of arc-extinguishing liquid, a pair of relatively stationary contacts mounted in the container and in the arc-extinguishing liquid, a conducting member for bridging said relatively stationary contacts, a unitary arc chamber into which said bridging member is movable, said arc chamber being substantially closed at the end toward which the bridging member moves in opening the circuit and having a relatively close fit with said bridging member adjacent said substantially closed end for causing liquid to flow in the chamber toward the opposite end thereof to aid in extinguishing the arcs.

11. In a circuit breaker, a container of arc-extinguishing liquid, a pair of relatively stationary contacts mounted in the container and in the arc-extinguishing liquid, a conducting member for bridging said relatively stationary contacts, a unitary arc chamber into which said bridging member is movable, said arc chamber being substantially closed at the end toward which the bridging member moves in opening the circuit and having a relatively close fit with said bridging member adjacent said substantially closed end for causing liquid to flow in the chamber toward the opposite end thereof to aid in extinguishing the arcs, and barrier means for confining the flow of fluid in the chamber largely to flow adjacent the ends of the bridging member where the arcs play.

12. In a circuit breaker, a container of arc-extinguishing liquid, a pair of relatively stationary contacts mounted in the container and in the arc-extinguishing liquid, a conducting member for bridging said relatively stationary contacts, a unitary arc chamber into which said bridging member is movable, said arc chamber having an elongated opening therein into which said bridging member fits substantially as a piston, one or more passages adjacent at least one end of the bridging member through which liquid is forced to flow through the arc in a direction opposite to the movement of the bridging member in the drawing the arc.

13. In a circuit breaker, a container of arc-extinguishing liquid, a pair of relatively stationary contacts mounted in the container and in the arc-extinguishing liquid, a conducting member for bridging said relatively stationary contacts, a unitary arc chamber into which said

5 bridging member is movable, said arc chamber having an elongated opening therein into which said bridging member fits substantially as a piston, and a narrow slot extending outwardly from each end of the chamber and into which the arcs may be moved.

10 14. In a circuit breaker, a container of arc-extinguishing liquid, a pair of relatively stationary contacts mounted in the container and in the arc-extinguishing liquid, a conducting member for bridging said relatively stationary contacts, a unitary arc chamber into which said bridging member is movable, said arc chamber having an elongated opening therein into which said bridging member fits substantially as a piston, and a narrow slot extending outwardly from each end of the chamber and magnetic means for moving the arcs outwardly toward the ends of said narrow slots.

15 15. In a circuit breaker, a container of arc-extinguishing liquid, a pair of insulated lead-in conductors extending into the container, a contact on the inner end of each of said conductors, a bridging member for completing the electrical circuit between said contacts, a single arc-extinguishing chamber having an opening through its upper end large enough to receive said bridging member, means mounting said arc-extinguishing chamber independently of and spaced from the inner end portions of said insulated lead-in conductors and the contacts thereon with its upper end below the level of the bottom of said contacts and without any solid material bridging the space between the upper end of the arc-extinguishing chamber and the inner end 20 portions of the insulated lead-in conductors, and said single arc-extinguishing chamber being substantially closed at its sides and lower end and having a relatively close fit with said bridging member at least adjacent the lower end thereof.
